UNITED STATES PATENT OFFICE.

WILLIAM T. CARNES, OF KANSAS CITY, MISSOURI, ASSIGNOR TO CARNES ARTIFICIAL LIMB COMPANY, OF KANSAS CITY, MISSOURI, A CORPORATION OF MISSOURI.

PHONOGRAPH.

Application filed December 19, 1923. Serial No. 681,511.

This invention consists in improvements in or relating to talking machines, and refers particularly to the sound boxes and needle holding mechanism thereof.

5 My improved sound box is so constructed that it receives the vibration from both sides of the diaphragm, and is provided with a partition adapted to neutralize the alternate compression and vacuum sound waves emanating from the opposite sides of the diaphragm, so that interference of said waves will be avoided. This construction also provides for a throat passage from the diaphragm to the tone arm of greater diameter 10 than is now used, which improves the quality of the tone. I have also provided an improved needle holding mechanism which provides sufficient elasticity and is free from all turning or sliding movements of metal 15 against metal, and when secured in place does not require adjustment.

These and other features of my invention are hereinafter set forth and pointed out and are illustrated in the accompanying 20 drawings, in which:

Figure 1, is a side view in elevation of my improved sound box and needle holder.

Figure 2 is a horizontal central section of the same on the line 2—2 in Fig. 1.

30 Figure 3 is a transverse vertical section of the same on the line 3—3 in Fig. 1.

Figure 4 is a section of the stylus holding mechanism on the line 4—4 in Figure 1.

Figure 5 is a horizontal central section of 35 the removable face portion of the sound box.

Figure 6, is a side view in elevation of a fragment of the sound-box and stylus holding mechanism on an enlarged scale.

Figure 7, is an enlarged section of the 40 same on enlarged scale on the line 7—7 in Fig. 6.

Figure 8 is a central longitudinal section of the stylus holding mechanism removed from the sound-box.

45 In these drawings A indicates the disc-like body portion of the sound box, which has a hollow neck A' integral therewith by means of which it is secured to the tone arm B of the talking machine.

50 The neck A' is provided with a vertical portion wall a which extends forwardly therein nearly to the center of the body portion A, the front end thereof being bifurcated as shown at a', to receive the dia- 55 phragm C of the sound box. The face plate

A² is secured on the body portion A, by means of screws a² in the usual manner, and gaskets b engaging the edge of the diaphragm C, are clamped between the body A and face plate A² when the screws a² are turned up to bring said parts A and A² together, thus firmly securing the diaphragm in place in the usual manner.

60 The interior of the neck A' is divided by the wall a into two sound passages b' and b² which extend forwardly to a point beyond the center of the diaphragm so that the sound waves generated on each side of the diaphragm C travel backwardly through said passage into the tone arm B of the 65 machine.

70 By means of the division wall a, the tone wave generated in the passage b' is partially separated from the tone wave generated in said passage b² by the same movement, and vice versa, and thereby minimizes any clashing of tone waves.

75 The sound box is provided with lugs H, H, on the periphery thereof which are spaced apart sufficiently to receive the needle holding mechanism therebetween.

80 The needle holding mechanism of my invention, shown herein, consists of a middle disc D' which is secured upon a plurality of flat spring metal strips E which are welded or otherwise permanently secured in radial slots in the periphery of the disc D. Also welded or otherwise permanently secured upon the ends of said flat spring metal strip E, are end discs F which engage the 85 lugs H, H and are firmly secured thereto by means of screws h, so that said discs F will have no movement with relation to said lugs H.

85 The end discs F, flat spring metal strips E and middle disc D form a unitary structure, the flat metal strips E permitting a degree of flexibility between the middle disc D' and the end discs F. Secured to the middle disc D is a needle holding socket 100 d wherein a stylus needle can be clamped by the thumb screw d'. Also secured to the middle disc D' is a needle lever D, the free end of which is secured to the central point of the diaphragm C. The strips of spring metal E, by reason of their flexibility, provide for the vibrating of the needle and allow the same to be communicated to the stylus arm D and diaphragm C. In this construction there is no movement of metal 110

against metal, and the vibrating movement of the needle and tone lever depends solely upon the torsion of the spring strips E, which eliminates all possibility of any squeak or rattle, and when the needle is clamped in place no adjustment is necessary, on account of expansion or contraction.

Having thus fully described my invention so that the construction and operation thereof will be obvious, I do not desire to be limited to the exact construction shown and described, as many modifications can be made therein without departing from the scope of my invention but what I claim as new is:

1. In an apparatus of the class described, a diaphragm, a sound-box enclosing both sides thereof and firmly clamping the edge thereof, a hollow neck communicating with the interior of said sound box, a division wall within said neck bifurcated at one end to receive a portion of said diaphragm, a needle holding mechanism secured on said sound box, and a stylus bar secured on said needle holder and said diaphragm.

2. In an apparatus of the class described,

a diaphragm, a sound-box enclosing both sides of and firmly clamping the edge of said diaphragm, a hollow neck on said sound-box adapted to be connected with the tone arm of a talking machine, a division wall in said neck bifurcated at one end thereof to receive said diaphragm and a needle holding mechanism including a stylus bar secured to said sound-box and to the central portion of said diaphragm adjacent to the bifurcated end of said division wall.

3. In a needle holding mechanism for sound-boxes, a pair of spaced lugs on said sound-box, said lugs being provided with openings on the same axial line, a screw in each of said openings, a nut-ring on each of said screws inside of said lugs, a plurality of flexible metal strips integrally secured to said nut-rings and equally spaced around the periphery of and extending from one to the other thereof, and a needle holding member, including a stylus bar, integrally secured to the intermediate portion of said flexible metal strips.

In testimony whereof I affix my signature.

WILLIAM T. CARNES.
